BRUSH MAKING MACHINE

Conrad Jobst, Toledo, Ohio, assignor to The Toledo Automatic Brush Machine Company, Toledo, Ohio, a corporation of Ohio

Application August 9, 1943, Serial No. 497,977

10 Claims. (Cl. 300—3)

1

The invention relates to brush making machines and has for its object increase in the speed of production and the elimination of certain defects inherent in constructions heretofore used.

In the present state of the art one type of brush-making machine largely used, simultaneously operates on two brush backs, boring the tuft-receiving holes in one back and setting tufts in the corresponding holes of the other back. It has been found that the time interval required for the setting of a tuft is less than that necessary for successfully boring a tuft-receiving aperture in a brush back, and consequently when these two operations are carried out simultaneously, the limit in speed of production is set by the boring operation. Brushes have also been manufactured by boring the brush backs in one machine and setting the tufts in the bored backs in another machine. It has been found, however, that the materials used for brush backs and also the shapes of such backs, render it practically impossible to transfer a back from one machine to another and to maintain exact registration of the holes with the tuft-setting means.

To avoid difficulties in both methods of brush manufacturing above described, I have devised a method in which the cycle of successive tuft-setting operations differs from the cycle of boring operations, while at the same time the brush backs remain in the same holder during both operations. I have further devised a machine in which a plurality of tuft-receiving holes are simultaneously bored in one brush back during the interval in which a series of tufts are set in the bores of another back. By these improvements the speed of production of my improved machine is considerably increased over that possible with the older type, while accuracy in registration is maintained.

In the drawings:

Fig. 1 is a sectional side elevation of my improved machine;

Fig. 2 is an end elevation thereof;

Fig. 3 is a plan view;

Fig. 4 is a vertical section through a portion of the turret, illustrating the friction drive and indexing mechanism;

Fig. 5 is a plan view of the indexing mechanism;

Fig. 6 is a longitudinal section through the multiple drilling mechanism;

Fig. 7 is an end elevation thereof;

Fig. 8 is an elevation of the opposite end;

Fig. 9 is a section on line 9—9, Fig. 6; and

Fig. 10 is an elevation of the cam controlling

2

the feeding movements of the multiple drilling mechanism;

Fig. 11 is an end elevation of a portion of Fig. 1 showing the controlling switches and operating mechanism.

As the tuft-setting mechanism is similar to that forming the subject matter of certain of my former patents, it need not be described in detail in the present case. However, generally described, it comprises a reciprocating member carrying the tuft-setting nozzle, and cooperating means for gathering the bristles of the tufts, and for driving and anchoring the same.

The tuft-setting mechanism generally indicated at A is mounted on a suitable frame B and is operated by an electric motor or other driving means (not shown) through a suitable transmission mechanism C. This transmission also includes a train D for driving a shaft E on which are mounted controlling cams F and F'.

The work holder is preferably in the form of a turret G, adapted to hold a series of brush backs which, through the operation of an indexing mechanism, are successively presented in operative relation to the tuft-setting mechanism. Inasmuch, however, as the reciprocating tuft-setting means has only a rectilinear path of travel, it is necessary to impart to the work holder additional movements for successively registering the holes in a bored back with said line of travel. On the other hand, as the boring mechanism must operate on a brush back on the same turret, and as the time required for completing a bore is longer than that required for the setting of one tuft, this necessitates maintaining a fixed relation between the work holder and boring mechanism during the interval between successive indexing operations.

To fulfill conditions just described, the frame B has mounted thereon a guideway H which, as shown, is slightly inclined from the vertical and with which is slidably engaged a movable head I. This head has at its upper end a transversely extending guideway I' in which is mounted a carriage J, capable of transverse reciprocation. The turret G is mounted on a portion of this carriage while upon another portion, there is mounted a multiple boring mechanism K. The head I is actuated to be raised or lowered in the guideway H by the cam F which engages a roller I² on said head. The carriage J is actuated by the cam F' which engages a roller L on a vertically extending lever L' centrally pivoted at L². The upper end of this lever has a roller L³ engaging a substantially vertical groove J' in a depend-

ing bracket J^2 on the carriage J . The cams F and F' are so fashioned that their simultaneous rotation will impart predetermined movements to the head I and carriage J which, in turn, will move the turret G according to a predetermined pattern of tufts to be set in each brush back. Also the speed of movement is limited only by the length of dwell required for the forming and setting of a tuft.

Multiple boring means

As previously stated, the multiple boring means is mounted on the carriage J , and therefore maintains a fixed relation to the turret G during all movements imparted by the cams F and F' for completing a tuft-setting cycle. This permits of simultaneously boring all of the tuft-receiving apertures at a relatively low rate of drill speed. Also, instead of continuously feeding the drills into the work, they may be advanced intermittently, so as to form separate small shavings instead of one continuous spiral shaving. This is advantageous in that it permits of easily clearing the drills after each multiple drilling operation.

The multiple boring mechanism may be of the type illustrated and described in my former Patent 1,661,179, issued March 6, 1928. In detail and as illustrated in Fig. 6, K is a frame mounted on the carriage J , forming a guideway for a slideable head K' . On this head are mounted a pair of parallelly arranged, spaced shafts K^2 , having mounted thereon at their rear ends gear wheels K^3 which, through intermediate gear wheels K^4 , are driven from a central gear wheel K^5 . The gear wheel K^5 is on a shaft K^6 which is connected by a splined coupler K^7 with a drive shaft K^8 . The arrangement is such that the head K' is capable of reciprocating movement in the frame K ; while maintaining the driving engagement between the shafts K^8 and K^6 . At the forward ends of the shafts K^2 are eccentric pins K^9 which engage a plate K^{10} , to impart thereto an oscillatory movement. K^{11} and K^{12} are spaced plates in advance of the plate K^{10} , mounted on the head K' , and these plates are bored to receive the drills K^{13} arranged in a pattern corresponding to the desired pattern of tufts. Each drill is bent at its rear end to form a crank K^{14} , the throw of which is the same as that of the eccentric pins K^9 , so that the oscillation of the plate K^{10} will simultaneously rotate all of the drills. A stripper plate K^{15} is mounted on the frame K at the forward end of the drills, in their retracted position.

For reciprocating the head K' there is provided the following mechanism: M is a pinion mounted on the shaft K^6 , to travel therewith and with the head K' . This pinion is of sufficient length to maintain intermeshing engagement with a gear wheel M' mounted on a shaft M^2 journaled in bearings on the frame K . On the shaft M^2 is a worm M^3 in engagement with a worm gear M^4 on a shaft M^5 extending transversely to the shaft M^2 and journaled in the upper portion of the frame M . M^6 is a cam also mounted on the shaft M^5 and having a peripheral engagement with a cam follower M^7 mounted on the upper end of a lever M^8 . This lever is fulcrumed at M^9 to the lower portion of the frame K , and intermediate the fulcrum and the follower M^7 has a pivoted shoe M^{10} engaging a vertically extending slot or channel M^{11} in the head K' . The arrangement is such that the rotation of the cam M^6 will impart to the lever M^8 a reciprocatory movement and a corresponding movement to the head K' which, in its forward phase, will

simultaneously advance all of the drills K^{13} and in its rearward phase will retract said drills. However, as above described, the forward advancement of the drills is not continuous, but in small steps, which is accomplished by properly fashioning the cam. Also, instead of continuing this step by step advancement throughout the full forward movement of the drill, the drill is retracted after drilling a portion of the depth

10 of the hole so as to clear it from chips or shavings, and then is again advanced to complete the boring to the full depth. Such movement is also accomplished by the fashioning of the cam, which completes the drilling and retraction of the drills in one cycle.

15 It is essential that the drilling cycle should be completed within the time interval required for the tuft-setting cycle, but it is not necessary that it should occupy all of this time. Thus provision must be made for the intermittent op-

20 eration of the driving shaft K^8 and maintaining this operation in timed relation to the operation of the tufting mechanism. Preferably the shaft K^8 is driven by an electric motor N mounted on the frame and having a universal coupling connection with the shaft. The motor is controlled by starting and stopping electric switches O and O' which are actuated by trip members O^2 and O^3 mounted on the shaft E . As this

25 shaft actuates the cams F and F' , the trips can be positioned in properly timed relation to the tufting cycle and to the indexing mechanism, which will now be described.

Indexing mechanism

30 35 The turret G has a series of individual holders G' thereon with which the brush backs may be engaged. One of these holders is positioned in operative relation to the tufting mechanism, while another holder is in operative relation to the multiple drilling mechanism. After the completion of each tufting cycle the turret is rotated one step to bring an unbored brush back into registration with the boring mechanism, and a bored brush back in registration with the

35 40 tufting mechanism. This is accomplished by the following mechanism. The turret G is revolvably mounted on a post G^2 extending upward from the carriage J , and on this post, beneath the turret, is also journaled a worm wheel P . This worm wheel is driven by a worm P' on a shaft P^2 , which latter is driven through the medium of a gear train P^3 from the gear wheel M' . Thus whenever the motor N is in operation, rotary movement will be imparted to the

45 50 worm wheel P . Secured to the worm wheel is a friction drive Q which engages an index plate R secured to the turret G . The index plate R is provided with locking notches R' corresponding in angular position to the holders G' on the turret, and one of these notches is normally engaged by a locking dog R^2 . The dog is pivoted at R^3 and is yieldably held in engagement with a locking notch by a spring R^4 engaging a lever arm R^5 . R^6 is a member slidably engaging a

55 60 bearing R^7 and provided with a finger R^8 . This finger, in the sliding movement of the member R^6 , is adapted to engage a pin R^9 on the lever arm R^5 and to rock said arm so as to disengage the dog R^2 . However, this disengagement is 65 only instantaneous, as the finger quickly passes beyond the pin R^9 , permitting the spring R^4 to return the dog. The member R^6 is preferably electromagnetically operated by a solenoid S which, when energized, will draw inward its core

70 75 member S' and impart a like movement to the

member R⁸. The member R⁸ is pivoted to the core at R¹⁰ so that in its return movement the finger R⁸ passes beneath the pin R⁹ without disturbing the position of the lever arm R⁵.

In the operation of the construction just described, the turret G is normally held against rotation by the dog R² so as to maintain fixed relation to the carriage J during the performance of the tuft-setting cycle. At the completion of this cycle the solenoid S is energized to withdraw the dog, whereupon the friction clutch Q will impart rotary movement to the index plate and turret. However, the almost instantaneous release of the dog R² will permit it to engage in the next notch R' of the index plate so as to again lock the turret in fixed relation to the carriage J.

Complete operation

The machine is adapted to operate continuously for any desired length of time. The operator places the brush backs in engagement with the holders G' on the turret G so as to be presented first to the multiple drilling mechanism. This, as previously described, operates at a relatively low speed of drill feed and with a step by step movement so that relatively small chips or shavings are cut in each step. After the drill has been advanced to approximately one-half the depth of the holes to be drilled, it is retracted so as to clear the drills from shavings by means of an air blast of a suitable air nozzle (not shown). The drills are then again advanced and the step by step feeding movement continued until the required depth is attained. During this operation the cams F and F' actuate the head I and carriage J to successively register the holes in a drilled brush back with the tuft-setting mechanism. However, as the multiple drilling mechanism is mounted on the carriage in fixed relation to the turret, such movements do not interfere with its operation. The drilling cycle need not necessarily occupy all of the time required for the complete tuft-setting cycle. Thus the motor N is deenergized at the completion of the drilling cycle and not again energized until the end of the tuft-setting cycle.

Electric switches O and O', operated respectively by the trip members O² and O³, control the starting and stopping of the motor. The motor N is, however, started slightly in advance of the indexing operation, so that before the dog R² is withdrawn from the plate R, rotary motion is imparted to the worm wheel P. Thus as soon as the dog is withdrawn, the friction drive Q will impart movement to the index plate to advance another notch R' into position for engagement with the dog.

The machine may be operated at the highest speed permissible for the tuft-setting operations for the time required for the complete cycle will be abundant for the performance of the multiple drilling operation.

What I claim as my invention is:

1. In a brush machine, the combination with a tuft-setting mechanism of a rotary work carrier movable to present bores in a brush back successively in registration with said tuft-setting mechanism, and means normally in fixed relation to said work carrier for simultaneously boring a plurality of tuft-receiving holes in an other brush back.

2. In a brush machine, the combination with a reciprocating tuft-setting mechanism, a carrier for a series of brush backs, and means for inter-

mittently moving said carrier through a cycle to present the bores of a brush back in one position thereon successively in registration with said tuft-setting mechanism; of means mounted upon and movable with said carrier for simultaneously boring all of the tuft-receiving holes of a brush back in another position thereon, and means operating between cycles for successively transferring said brush backs from said last mentioned position to said first mentioned position.

3. In a brush machine, the combination with a reciprocating tuft-setting mechanism, a carrier for a series of brush backs, and means for intermittently moving said carrier through a cycle to present the bores of a brush back in one position thereon successively in registration with said tuft-setting mechanism; of means mounted upon and movable with said carrier for simultaneously boring all of the tuft-receiving holes of a brush back in another position thereon, a common holder for both brush backs on said carrier, and means operating between cycles for moving said holder to transfer the brush back from said last mentioned position to said first mentioned position.

4. In a brush machine, the combination with a reciprocating tuft-setting mechanism, a work carrier, and means for intermittently moving said carrier through a cycle to present the bores of a brush back thereon successively in registration with said tuft-setting mechanism; of a work holder for a plurality of brush backs mounted on said carrier, a multiple drilling mechanism mounted on said carrier and movable therewith, and an indexing mechanism operating between successive tuft-setting cycles for moving said work holder to present said brush backs successively to said multiple boring mechanism and to said tuft-setting mechanism.

5. In a brush machine, the combination with a reciprocating tuft-setting mechanism, a work carrier, and means for intermittently moving said carrier through a cycle to present the bores of a brush back thereon successively in registration with said tuft-setting mechanism; of a turret mounted on said carrier and adapted to simultaneously hold a series of brush backs, a multiple boring mechanism also mounted on said carrier, and indexing mechanism operating between successive tuft-setting cycles for rotatably adjusting said turret to successively present said brush backs to said multiple boring mechanism and to said tuft-setting mechanism.

6. In a machine for forming brushes including means for presenting of brush backs successively to boring and tuft-setting mechanisms, of means for successively setting in one cycle all of the tufts of one brush back means for simultaneously drilling in an independent cycle all of the tuft-receiving bores of another brush back, and indexing means operating in the latter cycle after the completion of the drilling operation and itself completed within the limits of the tufting cycle.

7. A brush machine comprising a tuft-setting mechanism, a work holder for a series of brush backs, a carrier for said work holder, a multiple drilling mechanism also mounted on said carrier, means for moving said carrier to successively present the bores of one brush back to said tuft-setting mechanism in one cycle of its operation, and means for operating said drilling mechanism in an independent cycle to simultaneously bore all of the holes in another brush back, said drill-

ing cycle being included within the limits of said tufting cycle. 1000 Indexing means included. 10
8. In a brush machine comprising a tufting mechanism for successively setting the tufts in one brush back during one cycle of its operation, a multiple drilling mechanism for simultaneously forming all of the bores in another brush back in an independent cycle, the latter cycle being completed within the limits of the tufting cycle, and indexing means included in the drilling cycle. 10

9. In a brush machine, including tufting mechanism for successively setting the tufts in all of the bores of one brush back, a multiple drilling mechanism for simultaneously drilling all of the bores in another brush back during the tufting interval, said drilling mechanism including means for intermittently advancing the drills into the work in short steps to form separate small shavings of less than one-half spire length which are readily cleared from the drills when removed. 15

10. In a brush machine, including tufting mechanism for successively setting the tufts in all of the bores of one brush back, a multiple 20

drilling mechanism for simultaneously drilling all of the bores in another brush back during the tufting interval, said drilling mechanism including means for intermittently advancing the drills into the work in short steps to form separate small shavings of less than one-half spire length which are readily cleared from the drills when removed and also including means for withdrawing the drills after boring a portion of the depth to clear the shavings therefrom before completing the drilling operation. 10
